Fig. 3

Fig. 4

*Fig. 5**Fig. 6*FIG. 1 is a top plan view of a forepart of a shoe tree embodying my new design;

FIG. 2 is a side elevational view thereof;

FIG. 3 is a cross sectional view taken on the line III—III of FIG. 1;

FIG. 4 is a side perspective view of the forepart of the shoe tree shown in FIG. 2 showing the side opposite to that of FIG. 2;

FIG. 5 is a side elevational view of the same; and,

FIG. 6 is a side perspective view of the side shown in FIG. 2.

The characteristic feature of my design resides in the configuration of the forepart of a shoe tree having an indented toe together with a curved line one side only

emphasizing the slender curvature of the configuration as disclosed.

This is a division of design application Serial No. D-63,984, filed February 20, 1961 and now abandoned.

I claim:

The ornamental design for a forepart of a shoe tree, substantially as shown and described.
